ELECTRIC HEATER FOR FAUCETS.

Application filed November 13, 1920. Serial No. 423,913.

To all whom it may concern:

Be it known that we, OTTO GRAETZER, a citizen of the German Republic, and a resident of Zollikon, Switzerland, and OTTO F. BRUMAN, a citizen of the Swiss Republic, and a resident of Zurich, Switzerland, have invented a new and Improved Electric Heater for Faucets, of which the following is a full, clear, and exact description.

10 Our invention relates to improvements in electric heaters for faucets, an object of the invention being to provide an improved electric heater and improved automatic and circuit controlling means therefor.

15 Heaters of this character, as heretofore made, are usually constructed so that the faucet is at the same time the interrupter of the current. Thereby the electric current is inserted at the beginning of the water

20 supply and is interrupted at the closure of the same. Arrangements of this kind, however, have all kinds of inconveniences, as for instance, the impact of current which takes place every time when the current is inserted, which impact is disturbing in many ways. Besides this, such arrangements suffer under the disengagement of boiler scale whereby the electrodes deteriorate.

25 Furthermore, experience has shown that part of the electric current passes through the main pipe, whereby all kinds of difficulties may arise.

30 All these draw-backs are eliminated by our invention, which consists principally in a special arrangement, with which the inserting of the current takes place after the opening of the faucet and where the interruption of the current takes place before the closing of the faucet, that is to say, the electric switch, which is combined with the faucet, closes the circuit after turning the handle a small amount to open, and when turning the handle the other way (in closing) the electric current is interrupted before the faucet is entirely shut. Furthermore, the outer one of the two concentrical electrodes is provided with small lower and larger upper openings.

35 At the beginning of the water supply a continually ascending water column starts. At the moment of the inserting of the current the resistance of the water column is high on account of the small section, when 40 the column of water just begins to rise. The resistance decreases then when the column

is ascending, whereby the section is rising to its normal value. The impact of current is in this way reduced to such an extent that, for instance, incandescent lamps will 45 not show any sudden difference of light. At the same time there remains a water column between the electrodes after the current is taken off, which water slowly passes through the narrow bottom holes, whereby the electrodes are cooled, thus avoiding a vaporization of the contents and, consequently, the formation of boiler scale. The latter forms, as is well-known, a considerable electric resistance to the electric current, which reduces its action and the heat generated by it. The emptying of the space between the electrodes has another great advantage, which consists in the fact, that the current is cut down automatically, when the water 55 is turned off; thus without doing any damage to the apparatus.

Finally, there is, according to the invention, inserted an intermediate insulating fitting between the faucet, casing and the waterpipe with a view to avoid as much as possible the passage of the electric current to the waterpipe.

The invention is illustrated in the drawings, of which—

Figure 1 is a vertical longitudinal section taken through a faucet showing our improved heater located therewithin; and

Figure 2 is a section taken on the line 2—2 of Fig. 1.

A represents the body of the faucet, B the outer electrode, and C the inner electrode, both enclosed in the body A. The electrode B is in the form of a hollow or cup-shaped receptacle having, as disposed in the arrangement shown, a closed lower end and an upper end which is closed by a disk B' which is of insulating material. This disk B' surrounds the electrode C and serves to support and space the electrode B from the electrode C. The electrode C serves at the same time as water supply pipe controlled by a needle valve D which is regulated by the spindle F and the handle G, thus giving a tight joint against the water pressure. The valve spindle is fitted with a contact segment H which carries the current from the system I in such a way that the current coming from the positive pole enters the valve spindle through the contact segment H and goes as far as the inner electrode. On the negative side, a wire goes to the ex-

ternal electrode B. As soon as there is water between the electrodes, the current passes through it and heats the water as an electric resistance.

5 The outer electrode B has one or more lower holes, comparatively small so that when the handle G is only a little bit opened, the water begins to rise between the electrodes B and C. Almost the whole amount 10 of water then leaves the space through the large holes L, taking along with it, in the case for instance of very hot water, the air and steam bubbles, whereby the space is always completely filled with fluid. The hot 15 water then flows along the outer electrode downward and mixes itself with the water coming through the holes M. Finally it leaves the casing A at the exit opening N. Between the body of the faucet and the 20 waterpipes there is situated the insulating pipe K.

The operation of this invention is now as follows: The water contained in the pipe is 25 shut off by the needle valve D, while the remainder of water from the foregoing use of 30 the faucet has flown out through the openings M. The space between the two electrodes is therefore empty. The current supply is also cut off because of the contact segment H which makes contact only after 35 turning the spindle F a little. When turning the handle G to some extent the spindle F is lifted on account of the screw O. The needle valve is therefore opened and the water 40 enters through the inner electrode C into the space between the same and the outer electrode B. Owing to the small size of the lower holes only a very small part of the water can flow out; the greater part of it 45 forms a continually rising water column between the two electrodes. By turning the handle G farther the current is turned on through the contact segment and the current now finds its passage from one electrode to 50 the other. At first the section is small, the resistance great, but as the column rises, the section is enlarged, the resistance decreases, the current therefore increases finally to its 55 normal value. In this way we have an arrangement similar to the starting resistance of an electric motor which enables us to use the faucet in lighting circuits, every current shock being nearly avoided.

After using the faucet, the handle G is 55 closed whereby the current first is taken off by the contact segment H before the needle valve is closed. Therefore, there is yet a column of water between the two electrodes B and C. The remainder now flows through 60 the openings M out without the passage of the electric current through it. The electrodes have thus the opportunity to cool off and thus the formation of boiler scale is 65 avoided.

Such apparatus of the electrode types, 65 whereby the water gets into direct contact with the electric current, give to the latter the possibility to go to the waterpipe instead of returning over the electric wire. In order to avoid this evading of the current we 70 insert an insulating tube K between the waterpipe and the faucet which has a resistance of say about 10,000 ohms. The resistance is quite smaller than the one of the human body, so there will be no danger to touch 75 the faucet and the water jet coming from it.

What we claim as new is:

1. An electrical water heating device which comprises a cup-shaped electrode, a second electrode extending thereinto, and 80 means on the cup-shaped electrode whereby the flow of water therefrom varies in accordance with the level of the water therewithin.

2. An electrical water heater which comprises a hollow electrode having a plurality of different-sized apertures therein at different levels, so that the flow of water therefrom will vary in accordance with the level thereof.

3. An electrical water heater which comprises a cup-shaped electrode, a second electrode extending thereinto and spaced therefrom, means for insulatingly supporting the first electrode from the second, said means serving as a closure from the end of the cup-shaped electrode, means for introducing water between said electrodes, and means on the first electrode to permit a variable outflow of water therefrom.

4. An electrical water heater which comprises a hollow electrode having a closed bottom, said electrode having a plurality of small apertures near its bottom and a plurality of larger apertures near its top, so that the flow of water therefrom at different 105 levels will vary.

5. In an electrical water heater, the combination of a cup-shaped electrode having a plurality of small apertures near its bottom and a plurality of larger apertures near its top, a second hollow electrode extending into the first electrode, said second electrode acting as a pipe to convey water within the first electrode, an insulating disk closing the end of the first electrode and supporting it 110 from the second electrode, said disk embracing the second electrode, a needle valve in said second electrode to control the flow of water therethrough, a circuit contact on the needle valve, a circuit segment associated 115 with the needle valve and adapted when the valve is moved to engage with the contact whereby current is transferred through the needle valve to the second electrode, and electrical wires connected respectively to the segment and to the first electrode.

OTTO GRAETZER.
OTTO F. BRUMAN.
